UNITED STATES PATENT OFFICE.

JOHN TOMASZEWSKI, OF PINE BLUFF, ARKANSAS.

TRAFFIC-SIGNAL.

1,175,843.

Specification of Letters Patent. Patented Mar. 14, 1916.

Application filed August 10, 1915. Serial No. 44,783.

To all whom it may concern:

Be it known that I, JOHN TOMASZEWSKI, citizen of the United States, residing at Pine Bluff, in the county of Jefferson and State of Arkansas, have invented new and useful Improvements in Traffic-Signals, of which the following is a specification.

This invention relates to traffic signals, the object in view being to produce a practical light weight, water proof signaling device controlled electrically by the driver in his seat in the machine, whereby a directional indicator is operated to give notice to traffic officers and the operators of other cars and the general public as to whether the car equipped with the signal intends to proceed straight ahead or turn to the right or left.

A further object of the invention is to provide the primary controlling device or switch upon the steering wheel so as not to necessitate the driver removing his hands from the wheel in order to set the signal.

With the above and other objects in view, the invention consists in the novel construction, combination and arrangement of parts, as herein described, illustrated and claimed.

In the accompanying drawings:—Figure 1 is a side elevation of the traffic signal of this invention shown applied to an automobile, the view being partly broken away for the purpose of illustration. Fig. 2 is an enlarged vertical longitudinal section through the signal. Fig. 3 is a plan view thereof partly broken away to show the means for actuating the indicator. Fig. 4 is a detail perspective view illustrating the separable sections of the directional indicator or pointer. Fig. 5 is a plan view of the switch box.

Referring to the drawings A designates generally a casing or housing in which the major portion of the operating mechanism controlling the directional pointer is contained, the casing A comprising the main lower section 1 and the upper removable or cap section 2. Surrounding the main section 1 of the casing is a strap 3 which is extended in rear thereof to form a split loop 4 which is adapted to embrace the filling nozzle of the radiator of an automobile at

the foremost end of the car in order to support the signal in the most conspicuous position on the car, the split loop 4 being clamped tightly around the nozzle of the 55 radiator by means of one or more bolts 5.

Located and operating above the casing or housing A is the directional pointer 6 which is shown for convenience in the form of an arrow. This arrow as illustrated in 60 Fig. 4 comprises the forward or pointed section 6' and the rear or tail section 6'', the adjacent ends of said sections overlapping each other as indicated in the drawings and being provided adjacent to their overlapping portions with oppositely pressed substantially V-shaped offsets 7 which are designed to receive the squared upper end portion 8 of the shaft hereinafter particularly described, the overlapping portions of 65 the arrow sections being bolted, riveted or otherwise fastened together as at 9.

The upper portion of the shaft 8 extends through and is journaled in the top wall of the cap section 2 of the casing A and is 70 provided above the cap 2 with a washer or collar 10 to exclude water, dirt and other foreign matter from the interior of the casing A.

Within the upper portion of the casing 80 A, the shaft 8 is provided with an offset or crank portion 11 the end of which is reduced to form a shoulder 12 and threaded to receive a nut 13. A sector gear 14 is formed with a hole 15 to receive the lower 85 end of the shaft 10, said sector gear being clamped tightly on the shaft between the shoulder 12 and the nut 13. The teeth 16 of the sector gear mesh with a pinion 17 on the armature shaft 18 of a reversible electric motor 19 which is contained within the casing A and is provided with a supporting or base flange 20 bolted to the rear end wall of the casing.

21 designates a bracket having an attaching flange 22 which may be connected to the end wall of the casing A by means of the same bolts or fasteners 23 which secure the electric motor in place therein. The bracket 21 overhangs the motor and the 100 sector gear 14 is journaled thereon at 24. Therefore, as the sector gear 14 is turned

to one side or the other, it moves the lower end portion of the crank shaft 8 in a corresponding direction, thereby effecting a turning of the directional pointer to the respective side.

Mounted upon the sector gear 14 at diametrically opposite points are pinions 25, 26 designating the journals of said pinions and being shown in the form of screws.

10 These pinions coöperate with the pinion 18 of the motor when the pointer has traveled through an arc of ninety degrees from the central or neutral position thereof. Contractile springs 27 are connected at their 15 forward ends to the opposite corners or angles of the sector gear and are fastened at their opposite extremities to the interior of the casing A, said springs serving to return the sector gear 14 and the pointer to 20 a neutral or central position in which the pointer is directed straight ahead.

The lead wires to the electric motor 19 pass through a housing tube 28 which leads 25 from the casing A rearwardly through the dash of the vehicle into a switch box 29 mounted within convenient reach of the driver in his seat, said switch box containing a switch operated by a switch lever or handle 30.

30 31 designates the lead wires from the switch to the battery or other source of electrical energy carried by the car.

From the foregoing description, taken in connection with the accompanying drawings, the operation of the mechanism hereinabove described will be understood. When the operator desires to set the signal to indicate that he is going to turn to the right, he moves the handle 30 of the switch

40 in one direction. This energizes the motor so as to turn in the appropriate direction causing the pinion 17 to actuate the sector gear 16 and cause the same to sweep through an arc of ninety degrees from the central point.

45 When the teeth of the pinion 17 pass out of engagement with the teeth 16 of the sector gear, the pinion 17 meshes with one of the idler pinions 25 which by reason of frictional contact with its journal 26, prevents the teeth of the pinion 17 from meshing with or striking against the adjacent end tooth of the sector gear 16. This 50 enables the pointer to be maintained in its indicating position to the right as long as the electric motor is in operation.

55 By returning the switch lever 30 to its central or neutral position, the appropriate spring 27 acts to return the sector gear 14 to its normal position and causes the arrow to again 60 point straight ahead. By moving the switch lever 30 in the opposite direction, the same result is produced except that the motor is caused to revolve in the opposite direction and turn the pointer to the left. The switch

box 29 is preferably located on or adjacent 65 to the steering wheel of the machine so that the operator may control the directional pointer without removing his hands from the steering wheel, this being particularly valuable in making turns when it is important for the operator to have both hands 70 on the steering wheel.

The weight of the entire apparatus is approximately four pounds and is entirely 75 weather proof.

It is intended to enamel the pointer white so as to give the greatest possible contrast with the body of the car which is usually of a very dark color. This, however, is a matter within the province of the manufacturer.

In order to prevent the sector gear from turning through an arc of more than ninety degrees in each direction from the center, and in order to hold the pointer or indicator 85 in its right or left hand position, an electromagnet 32 is mounted within the casing A over the pinion shaft 18 and arms 33 are fastened to the spindles 26 of the idler pinions 25, the arms 33 acting as armatures and 90 being attracted by the opposite poles of the magnet 32. The armatures 33 thus act in conjunction with the magnet 32 as stops for limiting the movement of the sector gear 14 in opposite directions, and hold the sector 95 gear at one limit or the other of its movement while the adjacent pinion 25 is in mesh with the pinion 17. The electro-magnet 32 is in series with the electric motor 19 so that both are simultaneously energized 100 upon the closing of the switch which controls the circuit.

Having thus described my invention, I claim:

1. In a traffic signal, a directional pointer 105 mounted to sweep through a given arc, and electrically controlled means for actuating said pointer and sustaining the same in a convenient position, said means embodying a reversible electric motor, a sector gear by 110 which said pointer is carried, a driving pinion on the shaft of said motor meshing with said sector gear, idler pinions journaled on the latter and arranged to mesh with the driving pinion when either limit of movement of the sector gear is reached, a magnet 115 arranged about centrally of the sweep of the sector gear, and arms forming armatures carried by said sector gear and each attracted by said magnet to maintain one of 120 said idler pinions in mesh with the driving pinion when the pointer is at the limit of its sweep.

2. In a traffic signal, a directional pointer mounted to sweep through a given arc, and 125 electrically controlled means for actuating said pointer, said means embodying a reversible electric motor, a sector gear by

which said pointer is carried, a driving pinion on the shaft of said motor meshing with said sector gear, and idler pinions journaled on the latter and arranged to mesh with 5 the driving pinion when either limit of movement of the sector gear is reached.

In testimony whereof I affix my signature in presence of two witnesses.

JOHN TOMASZEWSKI.
